UNITED STATES PATENT OFFICE

CLARENCE WILLIAM McKEEN, OF KAPUSKASING, ONTARIO, CANADA

GUN SIGHTING

Application filed August 28, 1931. Serial No. 559,441.

The object of the invention is to attach a flashlight to a gun so that its beam of light will illuminate the object at which the gun is aimed. The flashlight is so mounted between the front and the rear sights that it obviates blurring attendant upon night shooting or when the daylight is so poor as to render it difficult to aim accurately.

A salient feature of the attaching clamp is that it holds the flashlight to one side of the barrel in order not to obstruct the sight.

A very distinctive feature of the invention resides in the provision of means for varying the clamp to adapt it to various sizes of guns.

Referring to the drawing, Figure 1 illustrates a flashlight attached to a rifle by means of the present invention.

Figure 2 is an enlarged cross section taken on the line 2—2 of Figure 1.

Figure 3 is a side elevation of the clamp shown in Figure 2.

Figure 4 is an edge view of links comprising the adjusting means of the clamp. The links are shown detached from each other.

Figure 5 is a plan view of Figure 4.

Like numerals of reference indicate corresponding parts in each of the figures throughout the drawing.

In the drawing, the reference numeral 6 denotes a conventional rifle to which the invention is applied. The barrel 7 has the usual front sight 8 and the rear sight 9.

10 designates the flashlight which is of suitable type for the purpose and is attached to the stock 11 intermediate of the gun-sights. It may be here remarked that the flashlight itself does not form a part of the invention as it may be of any make that is of suitable construction.

The flashlight is positioned to one side of the rifle at an angle of about 45° and attached by the clamp constituting the invention, which clamp is generally indicated by the numeral 12.

The clamp is composed of two bands 13 and 14 joined together at 15. The band 13 encompasses the flashlight and is split so that the ends 16 can be drawn together by the wing nut 17 on the bolt 18.

The band 14 is of like construction, the ends 19 being drawn together by the wing nut 20 on the bolt 21. It is preferable to line this band to prevent its marring the barrel and stock about which it is circumposed. A serrated lining 22 of rubber or other material may be employed for this purpose.

To provide for varying the band 14 to enable it to be adjusted to different sizes of gun stocks, means may be interposed in the band strip. The means may consist of a plurality of links 23 that can be readily detached to shorten the band. One end of each link has an open female element 24 and the other end has a pintle 25 transversely extended and joined to the body 26 at each end by a narrow neck of material 27 of a lesser thickness than the width of the opening of the female element 24. The band terminals 28 are similarly fashioned.

By this construction the links can be inserted and removed by merely swinging them to an abnormal angle that brings the narrow necks of material 27 in register with the opening of the respective female element so that the pintle can be slipped in or out of the engaged female element.

What I claim is:—

1. A clamp for attaching a flashlight to a gun, said clamp consisting of a band for encompassing the flashlight, a band for encompassing the gun, said bands being joined together and individually split, wing nuts and bolts for drawing the split portions of the bands together, and detachable links interposed in the gun band for varying its size.

2. A clamp for attaching a flashlight to a gun, said clamp consisting of a band for encompassing the flashlight, a band for encompassing the gun, said bands being joined to

gether and individually split, wing nuts and bolts for drawing the split portions of the bands together, and detachable links interposed in the gun band, each link having an open female end and a pintle at the other end joined to the body of the link by narrow neck portions of a lesser thickness than the width of the opening of the female end.

Signed at Kapuskasing, Ontario, Canada,
10 this 12th day of August, 1931.

CLARENCE WILLIAM McKEEN.
